SUSPENDED WORK SEAT FOR DENTISTS

Robert J. Haley, Longmeadow, Mass.

Application February 9, 1948, Serial No. 7,162

4 Claims. (Cl. 155—58)

1

This invention relates to movable work seats, and particularly to improvements in the class of seats intended for use by dentists while doing their kind of work.

Investigation will show that dentists generally stand while working on their patients. Stools are used by some dentists and special seats have been proposed, however, the general situation appears to be that many dentists find it too inconvenient to manage a stool in their work and for the most part they prefer to stand rather than experience the inconvenience of prior art seating structure.

In this situation the purpose of the invention to be disclosed is to provide a work seat for dentists that will not be in the way of any of his working movements, such as needed to place him in any of the positions where he wants to work on the patient nor in the way of his desired movements back and forth between the patient in the chair, his cabinet, sink or work table adjacent the patient's chair. The idea of keeping the work seat out of the way involves particularly the idea of keeping it out from under his feet and not blocking the walking area around the patient or the area in which the dentist wants to walk, stand and sit as he chooses.

The new seat and its utility can be best understood by reference to an example and an explanation of the example in relation to the dentist's work as he carries it on with his patient in the customary dental chair.

An example of the invention is shown by the drawings:

Fig. 1 is a side elevation of a dental chair for the patient and a work seat for the dentist which embodies my invention;

Fig. 2 is a cross section on line 2—2 of Fig. 1;

Fig. 3 is a plan view of a dentist's office illustrating a convenient position in which to have the track shown in Fig. 1 and Fig. 2;

Fig. 4 shows another form of the seat holding member;

Fig. 5 is a plan view of the seat or saddle shown in the side elevations of Fig. 1 and Fig. 4;

Fig. 6 is a side elevation, partly in cross section, of the same track as shown in Fig. 1, but illustrating a different trolley and hanging means for the work seat; and

Fig. 7 is a detail plan view partially in section of the carriage body member of the construction shown by Fig. 6.

The structure of the example in the drawings consists in track member 2 to be supported at a ceiling height in the dentist's operating or work

2

room. The ceiling is not shown but it will be understood from the position of track 2 in Figs. 1 and 3 in relation to the patient's dental chair 1. This track member 2 fastened and held at ceiling height, as by mounting it to hang from office building members or end posts, not shown, provides a ceiling track to be used for a hanging saddle or seat 3. The dentist can easily straddle this saddle. When he sits on the saddle his weight is hung from the ceiling track member, by rod 5, to which the saddle is fastened by clamp 4, hook 6, chain 7, and hanger 10, rotatably mounted on carriage or trolley device 8, with carriage wheels 9 engaged with the tracks of track member 2. Some desirable features of the elements mentioned will be explained later. Only the general aspect of the seat mounting is now being considered.

It will be clear from Figs. 1 and 3 that the floor 20 of the dentist's work room is free from any structural impediments due to the means for seating the dentist. He can walk about his office and patient's chair, between the latter and tool cabinet 11 (Fig. 2), work table 12 and sink 13. 25 Not only can he walk freely over all such floor area as he uses most but he can walk followed by his seat, as will be explained, and sit down at any one of the many work positions to which he will move.

30 The saddle 3, rod 5, and chain 7 are not only a lightweight structure because of their small total bulk, but, being pivotally hung from the wheeled carriage, they are parts which can be kept available and yet out of the dentist's way 35 with little or no inconvenience. The rod 5 may be of tubing and is about as convenient to handle as a cane or walking stick.

In the expected use, the height of saddle 3 above the floor may be adjusted for a particular 40 dentist in this way. He stands with legs slightly apart, as if he were about to work at the patient's head from a standing position. The saddle 3 is moved vertically, by hanging hook 6 into one or another link of chain 7, until the dentist can 45 sit astraddle by a slight bending of his knees. With the saddle adjustment close enough, the user can retain his contact with the saddle 3, so that when he walks from one position to another the saddle will follow his movements.

50 He can turn around 360° at any place on the floor below the extent of the ceiling track indicated in Fig. 3, and saddle 3 will follow his movements on foot and be available to take his weight off his feet when he merely bends his knees. The 55 dentist can, of course, dismount from the saddle

at will. When he does, it is useful to have the saddle remain in the position where he leaves it. Then he can remount with the least inconvenience.

The arrangement desired for this purpose is provided by distributing the weight of the saddle 3, rod 5, and chain 7, in other words the parts hanging from carriage 8, so that the saddle will be hung as if it were the weight on a plumb line, i. e. always vertically below its point of suspension from above. Thus when the dentist gets off his seat such seat will not swing out of the plumb line but remain in the plumb line, except, of course, in any case of its being pushed out by the user's movements it will return to, rather than remain in, the plumb line. This feature is built into the structure by the design for its weight distribution or by adding weights at the points desired to get the plumb line action.

Considering rod 5 of Fig. 1, its center of gravity would normally be in its long vertical portion. When the saddle is on the horizontal portion of rod 5, the saddle weight tends to move the bar into the position shown. In the modified bar 5a of Fig. 4 its weight or center of gravity can be located in the vertical line below the hook. The arrangement of bends in the rod places the saddle in the "plumb" line so that the weight of the saddle, provided the saddle is placed with its center of gravity on the plumb line, is not pertinent to the position of the rod. The form of Fig. 4 has the advantage of using less chain. When unhooked from a shorter chain (than in Fig. 1) the rod 5a can be put away and the remainder of the supporting apparatus is high enough to be more nearly out of normal sight.

Considering the hanger 10 of Fig. 1, its swivel joint with carriage or trolley device 8 is desirably of ball bearing construction as indicated or other easily turning bearing construction. It is useful to provide that any turning movement of rod 5 cause the turning of hanger 10 on its carriage bearing to avoid any substantial twisting of chain 7. Such twisting might be enough to cause the chain length to change and move the saddle seat up and down, as for example if the dentist in his work happened to turn around several times in the same direction. In other words, in the example shown the turning joint preferably moves freely to avoid chain twisting movements.

An adjustable padded back rest, not shown, could be attached by a clamp to the vertical portion of rod 5 as the saddle shown is to the horizontal portion. This is a minor convenience, however, not believed necessary in the most convenient use of the invention.

Of course, saddle 3 and rod 5 may be pivotally hung from a wheeled carriage of other construction than that shown in Fig. 1. A useful variation of structure is shown in Fig. 6. These two carriage constructions, with their way of making connection with links of chain, are preferred forms of structure and relate to some specific aspects of the invention as will be pointed out in some of the claims. In the broad aspect of the invention, however, the carriage may be a trolley device of any one of a variety of forms. The specific forms shown have the particular advantages in the combination for the dentist's use.

According to one feature of the invention, it is highly desirable to provide for a smooth travel of the supporting carriage when the dentist moves. Jerky movements should be substantially avoided. If the carriage starts and stops in other than smooth movements, these disagree-

able jerks will be transmitted from the carriage to the dentist.

The carriage construction 14 shown in Figs. 6 and 7 and the particular connections between the carriage and the work seat member 5 shown provide for a mode of operation which substantially avoids other than smooth movement of the carriage. Two trucks 15 and 16 of identical structure and with wheels 17 engaged with the tracks of track member 2, are joined together to make up the carriage construction 14, their rigid hanging members 18 rigidly attached to member 19. Thus carriage construction 14 is a substantial vehicle in that it has a vehicle body (member 19) suspended between two trucks. Hanger 20 passes through sleeve bearing 21 at the center of "body" member 19 positioned between the two trucks 15 and 16 and is free to swivel on ball bearings 22 as shown. Lateral movement of the hanger 20 is prevented, however, by close contact of the hanger with the bearing surface of sleeve bearing 21.

Hanger 20 is of a substantial length beyond that necessary merely to locate in it the bottom eye 23 for attaching whatever number of links of chain 7 desired. The purpose of this is to provide a depending rod, swivelled for very easy turning movement on its vertical axis and prevented from any tipping movement or deviation from the vertical.

The length of chain between the hanger 20 and rod 5 supporting the seat, permits the necessary swinging movement of the seat for it to follow the dentist's bodily movement. It will be noted that when the dentist moves and his seat follows, the chain makes a substantially greater angle for any such movement that it would if it were connected higher up and closer to the carriage. This larger angle results in a larger horizontal component of force to move the carriage on its track. Thus a much smaller movement of the dentist's body along the floor will cause an effective movement of the carriage at the ceiling level and there will be only a small lag between the horizontal movements of carriage and dentist with substantially no jerks as compared to a swinging chain connection at the ceiling level.

In its most useful aspect, the idea of the invention includes that of providing for a dentist's seat with very little bulk between the floor and ceiling of the office. What apparatus there is between the floor and ceiling in the examples of the invention shown is no more than a bicycle saddle, a rod similar to one piece of bicycle tubing, and a short piece of chain. It can be put away out of use about as easily as an umbrella or a cane and yet its scope when used without encumbering the dentist's office floor or working space, is much more extensive than any prior art seating arrangement for a dentist at work now known to me.

Having fully disclosed my invention, I claim:

1. Seating apparatus for a dentist's personal use while working on a patient, comprising a saddle small enough to be easily straddled when in sitting or standing position, a support carrying the saddle and projecting backwardly from its rear side a short distance to be offset from a user on the saddle, then upwardly higher than the user's head will be when in sitting or standing position astride the saddle, then forwardly to a point generally overlying the saddle, then vertically to a ceiling level, a horizontal track to be supported at such ceiling level, a trolley device movable on said track, said support from

said saddle including an upper swivel joint means hanging from the trolley device for suspending the support construction between the saddle and the trolley device, all in form adapted for use substantially as disclosed.

2. In apparatus for the use disclosed the combination of a ceiling track, a pair of spaced trucks riding on the tracks, a body member suspended from said trucks and fastened to them so as to prevent relative movement, the body member being close to and parallel to the track, said body having a bearing centrally thereof, a rigid rod mounted in the bearing to depend vertically from the body a substantial distance from the ceiling track to provide substantial clearance for moving the trucks and said body horizontally, said bearing being of a type permitting free turning on a vertical axis and preventing tipping movement of the rod, a generally C shaped rigid rod like frame member, a saddle attached at the bottom horizontal portion of such member, a short flexible member connecting the upper end of said frame member to the lower end of said rigid rod, all constructed and arranged for a dentist's seat to move with him when he walks a floor below the ceiling track and move the body member suspended by its trucks smoothly and with little lag between the dentist's movements and the movement of said trucks and suspended structure.

3. Seating apparatus for a dentist's personal use while working on a patient, comprising a saddle small enough to be easily straddled when in sitting or standing position, a support carrying the saddle and projecting backwardly from its rear side a short distance to be offset from a user on the saddle, then upwardly higher than a user's head will be when in sitting or standing position astride the saddle, then forwardly to a point generally overlying the saddle, then vertically to a ceiling level, a horizontal track to be supported at such ceiling level, a carriage device movable on said track, said support con-

struction from said saddle having vertically adjustable suspending means at the top thereof including a swivel joint and hanging from said carriage device for supporting said saddle substantially as disclosed.

4. Seating apparatus for a dentist's personal use while working on a patient, comprising a saddle small enough to be easily straddled when in sitting or standing position, a support carrying the saddle and projecting backwardly from its rear side a short distance to be offset from a user on the saddle, then upwardly higher than a user's head will be when in sitting or standing position astride the saddle, then forwardly to a point generally overlying the saddle, then vertically to a ceiling level, a horizontal track to be supported at such ceiling level, a carriage device movable on said track, said support from said saddle including a swivel joint and suspension means connected to the carriage device for hanging the saddle from the carriage device, the center of gravity of said saddle normally being in a direct vertical line below the connection of said suspension means with the carriage whereby said saddle acts as the weight of a plumb line in the operation of said apparatus.
